UNITED STATES PATENT OFFICE.

GEORGE E. SENSENEY, OF HOLYOKE, MASSACHUSETTS, ASSIGNOR TO THE MARVEL-LUM COMPANY, OF HOLYOKE, MASSACHUSETTS, A CORPORATION OF MASSACHUSETTS.

ORNAMENTAL PAPER AND PROCESS OF PREPARING SAME.

No Drawing.

Application filed May 19, 1921. Serial No. 470,924.

To all whom it may concern:

Be it known that I, GEORGE E. SENSENEY, citizen of the United States, residing at Holyoke, in the county of Hampden and State 5 of Massachusetts, have invented new and useful Improvements in Ornamental Papers and Processes of Preparing Same, of which the following is a specification.

This invention relates to a novel process 10 for producing variegated and ornamental color effects upon paper, and to the product of the said process.

My process may be carried out in numerous variations according to the special effects desired, not only in respect to the choice 15 of colors and the vehicles therefor, but also as regards the manipulative features of the process.

A characteristic feature of my process 20 consists in subjecting paper of any texture or surface finish to a diversified mechanical stressing action distributed more or less throughout its area which will alter the structure of the paper stock in regular or irregular 25 lines or areas and thus lessen or break down the resistance of the paper in such lines and areas to color penetration. Creasing, crumpling and crinkling the paper will supply the diversified mechanical stresses 30 mentioned and produce the regular or irregular lines of weaker resistance. This creasing or crumpling action may be effected by hand or mechanically by pressure rolls, or other means.

35 The results obtained by such diversified breaking down of fibrous resistance in the paper for non-uniform color penetration will be enhanced by the presence of a color "resist," i. e. a material tending to resist 40 color penetration, impregnated in or coated upon the paper before said creasing or crumpling action takes place. Such a "resist" is provided by the "size" content of the paper which it receives in its ordinary 45 course of manufacture, but in the case of slack-sized paper which is absorbent, albumen, casein or waxy compositions may be applied as a "resist."

It is important to note in my process that 50 both the fibrous texture of the paper and the impregnated or coated "resist" is made more penetrable to the coloring agent by the creasing and crumpling of the paper preparatory

to the application of the color. The color or color-modifying agent may be applied to the 55 paper thus prepared in any suitable manner and in any regulated amount necessary to give the desired result, as by immersing the paper therein or spraying or brushing the paper therewith. The color or modifying 60 agent will be taken up more readily at the lines and adjacent areas of greater penetrability where the paper stock and resist 65 have been broken down. It will be readily understood that according to the special 70 conditions of the process the effects produced may be indefinitely varied, not only as regards pattern and color, but as regards the production of shaded effects and the blending of colors.

A simple specific embodiment of my invention may be carried out in the following manner:

Paper which may be either sized or unsized is treated with any substance, including those above mentioned as appropriate resists, which will prevent or substantially retard the absorption by the paper of water or aqueous solutions. Any oil or oily preparation will serve this purpose. The treated paper is then creased or crumpled, either by hand or by mechanical means, and, preferably after being again flattened out by any suitable ironing operation, is treated with an aqueous solution of a dye, which may if desired carry also a suspended pigment. The paper may then be pressed and dried, and will exhibit a variegated surface effect due to the irregular penetration of the color. For a further color effect, the sheet may then, if desired, be treated with an oil color, the oil preferably carrying a dissolved or suspended color or both, and the excess of oil color removed by wiping. The color will be taken up largely at the penetrable lines or areas, enhancing the variegated effect; but it will also be taken up to a lesser degree over the entire surface of the paper, by reason of the penetrability of the oil resist to the oil color. The ironing operation of flattening the paper after being creased, partially smooths the surface thereof but does not entirely eradicate the ridges and uneven surface produced by the crumpling and creasing action. Therefore, if the oil color 100 be brushed or wiped on the paper, the color

will accumulate against the ridges or uneven projections of the creased paper to produce a desirable toning effect to the intensified areas of color. The paper is then finished in any desired way, according to the particular effect desired, by such operations as calendering, plating, embossing and the like.

In a further simplification of my process it is applicable directly to the treatment of 10 papers of any surface or texture, whether coated or not, provided they carry sufficient size so that the crinkling or other mechanical treatment will suffice to bring about substantial variations in absorptive capacity for 15 liquids. According to this modification, the paper is crinkled or otherwise mechanically treated to form regularly or irregularly distributed, relatively penetrable lines or areas; and is then flattened out and wiped or otherwise 20 coated with any coloring agent, such as a water color or an oil carrying dissolved or suspended colors or preferably both dissolved and suspended colors. The color and its vehicle penetrate to the greatest extent 25 at the local areas of relatively high absorptive capacity, producing variegated and highly ornamental effects, as described above. This penetration of the color in varying degree at different portions of the 30 paper will also produce a variegated and ornamental effect at the side of the paper opposite to that on which the color is applied due to the uneven penetration of the color through the paper. The excess of the 35 coloring agent is then removed by wiping, and the paper thereafter finished in any of the ways above mentioned. In this embodiment of the invention it is to be noted that the conditions for application of the 40 color are so chosen, and the nature of the ornamental effects are of such type, that an ordinary tub-size, or a surface size or coating, is capable of performing the essential functions of a resist, so far as permitting 45 the production of variegated ornamental effects is concerned.

It will be understood by those skilled in this art that the operation may be modified in various ways without departing from the 50 spirit of my invention. Among the modifications referred to I desire particularly to mention the following:

The resists used need not be absolute color-repellents but may possess a certain solvent 55 power for the color, or at least permit a certain penetration of the color. This is the case, for example, with the albuminous resists when the color is applied in an aqueous vehicle, and also with oil resists when the 60 color is applied in an oily vehicle. It results from this that whereas the color reaches the fiber in a concentrated form where the resist is locally broken down, it reaches it in a relatively dilute form where the resist 65 is intact, the resist acting in a sense as a

diluent for the color. In this way variegated, shaded, and blended effects may be produced.

Instead of applying a dye following the application and local breaking down of the 70 resist, I may produce essentially similar effects by uniformly dyeing the paper before or at the time the resist is applied, and then locally removing the dye by the use of an appropriate solvent, bleaching agent, or 75 other color-modifying agent, after the breaking down operation.

The sizing and dyeing may be combined in a single operation, the dye being carried in the sizing bath. If desired, different dyes 80 may be applied from opposite sides of the paper, as for example, by floating, spraying, brushing, or like operations.

The resist may be transparent, but in many cases I prefer to use it as a vehicle 85 for transferring dissolved or suspended color to the fibers.

What I claim is:

1. The process of producing ornamental color effects upon paper, which consists in 90 subjecting the paper sheet to distributed mechanical stresses adapted to produce local areas of relatively high penetrability; and then applying a color-modifying liquid to the treated sheet, whereby the non-uniform 95 penetration of the liquid produces a variegated color effect.

2. Process according to claim 1 wherein the paper carries a resist of a character to 100 permit limited penetration of the color.

3. Process according to claim 1 wherein the color-modifying liquid carries a suspended pigment.

4. Process according to claim 1 wherein the fibrous stock of the paper is impregnated 105 with a resist.

5. The process of producing ornamental color effects upon paper which consists in crumpling or creasing the paper to produce irregular crease line areas of high penetrability, then flattening said sheet and then applying a color-modifying liquid to the sheet whereby the non-uniform penetration of the liquid produces a variegated color effect. 110

6. The process of producing ornamental color effects upon paper which consists in crumpling or creasing the paper to produce irregular crease line areas of relatively high penetrability, then subjecting said sheet to an ironing operation to partially smooth out the surface thereof and then brushing or wiping a liquid color upon the surface of the sheet whereby the non-uniform penetration of color into the body of the paper and the uneven distribution of color upon the surface of the paper produces a variegated color effect. 115

7. A colored ornamental paper sheet having line defining portions which are of rela- 120 125 130

tively higher penetrability to a color modifying agent than other portions of said sheet, said paper sheet showing a variegated color effect due to the non-uniform absorption of a coloring agent in said different portions of said sheet.

8. A colored ornamental paper sheet having line defining portions distributed throughout said sheet in irregular pattern, 10 which are of relatively higher penetrability to a color modifying agent than other portions of said sheet, said paper sheet showing a variegated color effect due to the non-uniform absorption of a coloring agent in said different portions of said sheet.

9. A colored ornamental paper sheet having creased portions which are of relatively higher penetrability to a color modifying

agent than other portions of said sheet, said paper sheet showing a variegated color 20 effect due to the non-uniform absorption of a coloring agent in said different portions of said sheet.

10. A colored ornamental paper sheet having creased portions distributed throughout 25 said sheet in irregular pattern which are of relatively higher penetrability to a color modifying agent than other portions of said sheet, said paper sheet showing a variegated color effect due to the non-uniform absorption 30 of a coloring agent in said different portions of said sheet.

In testimony whereof I have affixed my signature.

GEORGE E. SENSENEY.
